METHOD OF AND MEANS FOR CONTROLLING VEHICULAR TRAFFIC

Lester L. Bosch, Cincinnati, Ohio

Application May 20, 1938, Serial No. 208,959½

7 Claims. (Cl. 177—311.5)

This constitutes a continuation in part of application Serial No. 81,747, filed by me on May 25, 1936, under the same title which identifies this case.

The high accident toll incident to the operation of vehicles is well known, and many devices and methods have been contrived for the purpose of limiting, controlling, or otherwise regulating their speed of operation. However, today still the accident toll remains excessive and its reduction a challenge to the civilized world.

My invention, herein described, has as its object the reduction of the accident rate thru the use of a new method of control, a method that regulates the operation of vehicles according to conditions. That is, my invention takes into account the fact that speeds of operation should be slower—1, at night than at day; 2, at times of bad driving conditions such as rain, snow, sleet, fog, etc. than for dry, clear pavements or atmosphere; 3, for inexperienced operators; 4, for operators with bad performance records; 5, for operators who have been found guilty of infraction of traffic laws; 6, for operators who are somewhat handicapped (if granted an operator's franchise at all); 7, for vehicles of subnormal condition; 8, for vehicles having less than normal effective braking power per unit weight; 9, for certain trucks and busses than for pleasure cars—or in general, for safety, that the speed of operation should be slower whenever the distance of perception, the reaction time of the operator, or the braking distance is increased beyond normal; in other words, that the speed of operation should be reduced whenever a condition or any given combination of conditions increases the overall stopping distance beyond normal, and further that the greater the number and magnitude of adverse conditions the greater should be the reduction in speed. Likewise, in general, the higher the rate of speed of the vehicle the greater should be the reduction for any given set of adverse conditions. For example, where speeds of twenty (20) and fifty (50) miles per hour may be allowed respectively on a bright, clear day, speeds of but fifteen (15) and thirty-six (36) miles per hour respectively might be allowed on a rainy night, a reduction of only five (5) miles per hour for the low speed but fourteen (14) miles per hour for the higher speed.

In the foregoing example, as well as those others given in this specification, the arbitrary factor of approximately 0.85 has been used for each reduction in speed from normal. One adverse condition, therefore, would require all speeds to be reduced to 85% of normal, two adverse conditions would require speeds to be reduced to 72% (.85 × .85) of normal, three adverse conditions to (.85)³ or 61% of normal, etc.

My invention allows for the practical applica-

tion of this derating principle by the zoning of highways into zones of definite variable speed limits depending upon conditions instead of fixed speed limits as at present. For instance, while 5 forty (40) miles per hour might be allowed on some particular highway at present, day or night, rain or clear, old truck or new car, this would not be true under the zoning method described herein and constituting a part of my invention. At 10 night, in the rain, for an inexperienced operator, for vehicles of poorer classification, etc. the allowable speed limits of any particular section of a highway would be reduced individually for each operator depending upon the overall classification of his vehicle as operated. This reduction would take place automatically, the same highway zone marker conveying different allowable speeds for each vehicle-operator-condition classification.

As an exemplary embodiment, I have disclosed in the accompanying four sheets of drawings means by which (a) the speed zones may be established, (b) the vehicle unit classified in accordance with operating conditions, and (c) the coordination of these with means on the vehicle so as to effect an improved method of traffic control or regulation.

My zoning method consists essentially of designating the various sections of highways by suitable zone numbers, symbols or characters, of classifying vehicles according to their type, kind, service, size, weight, designed speed, braking power, general condition, etc., of classifying operators according to previous experience, records, habits and qualifications, of designating adverse driving conditions, etc., and of coordinating these with means on the vehicle for indicating to the operator a state of compliance or non-compliance with the dictates of each zone marker for his particular vehicle-operator-condition classification.

It is anticipated that relatively few different highway zones would be required to adequately regulate traffic. For instance, using a system of 45 numbering zones, zone 1 might allow speeds of travel roughly corresponding to twenty (20) miles per hour for operation under the most favorable overall conditions, zone 2 up to thirty (30) miles per hour, zone 3 up to forty (40) miles per hour, zone 4 up to fifty (50) miles per hour, and zone 50 5 up to sixty (60) miles per hour, the limits of each zone being reduced corresponding to the number and magnitude of unfavorable conditions affecting the particular vehicle as operated. As 55 above indicated, for one declassification speeds of 85% of normal might be permitted, and 72% of normal for two declassifications.

The drawings indicate a symbolic character for each zone. However, a large numeral on a marker might be employed, or for simplicity and

economy in the transition from the present marker system to the zone system, the first digit of the present speed marker might be used to designate the zone number. That is, the three (3) of thirty-five (35), the two (2) of twenty-five (25), the one (1) of fifteen (15), the four (4) of forty-five (45), etc. might designate to those residing within the particular political subdivision speed zones three (3), two (2), one (1), and four (4) respectively, and to those residing outside the political subdivision and not in their resident area subject to the zoning principle, the regular limits shown on the marker, namely thirty-five (35), twenty-five (25), fifteen (15), and forty-five (45) miles per hour respectively.

In addition to the means of indicating to the operator compliance or non-compliance with zone dictates, I have provided in my invention a warning signal which would be given for a short duration whenever the vehicle's speed increased to that of a higher zone. If speed corresponding to the higher zone were permitted, the warning need not be heeded. Provision is also made for the giving of this same signal whenever the vehicle is brought to a legal stop, thereby giving the operator further information as to compliance with legal requirements and further assisting him in his efforts to avoid infraction of traffic laws.

Another object of my invention is the display of signals external to the vehicle showing the speed range, and the equivalent speed, or speed in terms of zones at which the vehicle is being operated. Similar signals would also be displayed within the vehicle for the further guidance of the operator, and in general the arrangement, number, color, etc. of the signals displayed to the operator, those displayed to others, and the highway zone markers would be similar or related in such a manner as to facilitate compliance with the law and to observe the operator's compliance or non-compliance as the case may be.

These signals may be audible, visual, mechanical, semaphores, illuminated, electromagnetic waves, or any suitable combination or arrangement. They would be given by virtue of the vehicle's speed of operation and would be entirely out of the control of the operator except as he operated the vehicle at different speeds and as he may or may not recognize certain conditions, which recognition could also be made known to others.

In order to prevent the frequent changing of these signals when at the transition point from one speed range to another, as well as to protect the operator against citation for very short violations occurring when passing another vehicle or by an unconscious speeding up, a slight time delay is provided between the time the higher

zone speed is reached and the signal for that zone is given, during which interval the operator is given the warning signal.

Traffic violations could therefore be easily and accurately determined without setting speed traps, clocking vehicles or in any manner jeopardizing the lives of enforcement officers and others. Dispute as to violation of the traffic laws would be minimized since the signal displayed by the operation of the vehicle itself would be the means for determining violation and not by necessity the officer's speedometer as is the present practice.

The fact that others are being informed of the vehicle's speed and that citations may be given so readily would have a very tempering and salutary effect upon every operator.

None of the signals displayed or any of the means herein provided would of necessity interfere with the vehicle's operation such as occurs with governors, because full power would be available at all times and for any emergency.

In order to set forth a concrete example of how conditions may affect the regulating or controlling of traffic by the provision of my invention, let it be assumed

1. That the proper authorities would set up four arbitrary vehicular classifications, namely class 1, 2, 3, and 4, with class 1 vehicle representing the highest classification.

2. That the proper authorities would set up three arbitrary operator classifications, namely class 1, 2, and 3, with class 1 operator representing the highest classification.

3. That means be provided on each vehicle so that whenever its external lights are turned on, the vehicle unit would suffer a declassification.

4. That means be provided on each vehicle so that whenever the operator recognized bad driving conditions such as wet pavement, rain, sleet, fog, etc., or turned on the windshield wiper, the vehicle unit would suffer a declassification.

5. That the proper authorities would designate the resultant overall classification of a vehicle for the particular condition under which it is operated as an overall vehicular-unit classification of A, B, C, D, E, F, and G, with A being the highest, and with classification B, C, etc. representing one, two etc. deratings as may occur due to any combination of vehicle, operator or condition declassification.

6. That the proper authorities would set up arbitrary highway speed zones of arbitrary speed limits for each zone for each overall vehicular-unit classification, an example of which is shown in the following table, where six zones are indicated and their respective upper speed limits in miles per hour.

	Zone 1	Zone 2	Zone 3	Zone 4	Zone 5	Unlim- ited zone
Overall vehicle-operator condition classification:						
A-----	20	30	40	50	60	Over 60.
B-----	17	26	34	42	51	Over 51.
C-----	14	22	29	36	43	Over 43.
D-----	12	18	25	31	37	Over 37.
E-----	10	16	21	26	31	Over 31.
F-----	9	13	18	22	27	Over 27.
G-----	8	11	15	19	23	Over 23.
Highway zone marker No.-----	1	2	3	4	5	End of zone 5. 5 lights flashing.
Vehicle signal displayed to others-----	1 light	2 lights	3 lights	4 lights	5 lights	

It is apparent that by various combinations of elements these six zones may be indicated by fewer than five signals. Also it is to be pointed out that both the number of zones and the speed range in each zone are arbitrary. As a rule it would not be expected that the higher zone limits would be generally legalized. While a number of authorities might adopt speeds roughly approximating those as shown above for zone 5, only a relatively few would be expected to establish such unlimited speed zones as represented by zone 6.

These and other objects of the invention will become apparent to those versed in the art in the following description of one particular form of the invention which is more or less diagrammatically illustrated in the accompanying drawings, and which constitute a counterpart of the system and invention itself in which:

Fig. 26 is a section of Fig. 27 taken on line F—F.

Fig. 27 is a front instrument panel view of Fig. 25.

Like characters of reference indicate like parts throughout the several views in the drawings.

Referring first to the speed zone markers, Figs. 1, 2, 3, 4, and 5, as well as the map, Fig. 6, in which these markers are shown in diagrammatic form. It will be noted that for simplicity only five instead of six speed zones have been established. Each marker is supported by some suitable structural member 1 to which I have attached a zone number marking tag 2, reflector buttons 3, and background member 4, the shape of which is distinctive for each of the five zone markers herein illustrated. Inscribed on this background member 4 are suitable characters. In this particular arrangement shown, the number of circles 5 inscribed on the marker 4 correspond to the number of the particular zone marker, one ring for zone 1, two rings for zone 2, etc. The configuration of these rings 5 is distinctive for each of the respective zones and corresponds with similar distinctive signals on the vehicle to be subsequently described.

In the arrangement I have shown, the center of ring 5 is a reflector of either white or amber color and arranged to be visible at day or night. It is, of course, possible to make the center an illuminated signal if so desired. In Fig. 1 the center 6 is white; in Fig. 2 are shown two rings 5, the one at the left having a white center 6, and the one at the right having an amber center 7; in Fig. 3 are three rings 5 with the center 6 of the left and the right rings being white and the center 7 of the middle ring being amber; in Fig. 4 are shown four rings 5, the first and third from left having centers 7 of amber and the second and fourth having centers 6 of white; Fig. 5 shows five rings 5, the first and fourth having centers 7 of amber and the second, third and fifth having centers 6 of white. The particular inscriptions, outline, form, colors, and arrangement are significant only insofar as thereby forming a distinctive and easily distinguishable marker by day or by night for each respective zone.

I have painted the supporting member 1 and placed reflector buttons 3 on it so as to further make the marker conspicuous and to convey information as to zone changes. For instance, if the particular marker is the beginning of a higher zone, green (Gr) reflector buttons and characters have been placed on it. If the marker indicates that the same zone is still in effect and is simply a reminder of that zone, amber (Am) buttons and characters have been employed. If the marker indicates a change to a lower speed zone, then red (R) buttons and characters have been used. As a still further means of calling attention to speed zone changes, the marker 2 attached to member 1 may be shaped or positioned to indicate the character of the change. For instance, if the change is to a lower zone, the marker might be of diamond shape, characteristic of the rather universally adopted highway danger sign. An example of this is shown in Fig. 3 where the marker 2 is diamond shaped. In the other figures the marker 2 is square and indicates either the same zone or a change to a higher zone. Obviously, the zone number marker 2 may be inscribed on the background 4; that is, it is not necessary that marker 2 and background member 4 be separate elements.

The markers referred to above are shown diagrammatically on Fig. 6 by round circles with numbers in their centers, a "1" in the circle

indicating a marker as shown in Fig. 1, a "2" indicating a marker as shown in Fig. 2, a "3" a marker as shown in Fig. 3, a "4" as shown in Fig. 4, a "5" as shown in Fig. 5, with the subscript letters R, Am, and Gr indicating respectively the beginning of a lower speed zone, the continuation of the same speed zone, and the beginning of a higher speed zone, and characteristically marked as heretofore described. Also on Fig. 6 are shown vehicles 8 to 19 inclusive operating on a crossroad CR-RD and main highway Hi through the business Bu and suburban Su sections of the town Tn and rural Ru sections of the highway.

In order to further explain how my method of traffic control provides for the individual regulation of each vehicle and operator for the particular existing conditions and assuming vehicle-operator-condition classification to be set up by the proper authorities as previously outlined, I have assigned in the following table a vehicle and operator classification for each of the vehicles 8 to 19 inclusive shown in Fig. 6, and also have shown how such classifications would be modified by darkness and or bad driving conditions.

Vehicle units, Fig. 6	Vehicle classifica- tion	Operator classifica- tion	Overall vehicle- operator classifica- tion	Overall unit classification	
				For darkness or bad driv- ing condition	For darkness and bad driv- ing condition
8	1	1	A	B	C
9	1	2	B	C	D
10	1	3	C	D	E
11	2	1	B	C	D
12	2	2	C	D	E
13	2	3	D	E	F
14	3	1	C	D	E
15	3	2	D	E	F
16	3	3	E	F	G
17	4	1	D	E	F
18	4	2	E	F	G
19	4	3	F	G	G

Vehicle unit 8 would therefore have an A classification, the best, and would be allowed to travel at higher rates of speed in each respective zone than would the rest of the vehicle-units. Units 9 and 11 would have the next highest classification, units 10, 12, and 14 the next highest, etc.

Assuming each of the vehicles 8 to 19 inclusive being in motion, then at the instant the vehicles are at the positions shown in Fig. 6, vehicle unit 8 would be required to come to a legal stop; vehicle unit 9, according to marker 20, is restricted to travel at the speeds allowed in zone 1 for its particular overall vehicle-operator (V-O) classification B; vehicle unit 10, according to marker 21, would be permitted to operate at speeds allowed in zone 2 for its particular V-O classification C; vehicle unit 11, while also still in zone 2, marker 22, would be allowed higher speeds since its particular V-O classification is B and therefore higher than that of vehicle 10; vehicle unit 12 with a V-O classification of C is required to slow down to zone 1 speeds upon encountering marker 24 at school 23, and then permitted to resume speed of zone 2 at marker 25; vehicle unit 13 would be permitted to travel at zone 2 speeds having passed marker 25; vehicle units 14 and 15 would likewise be permitted to travel at speeds allowed in zone 2 for their respective V-O classifications of C and D; vehicle unit 16 would be allowed to increase its speed to that allowed by zone 3 in accordance with marker 26 with its Gr sub-markings; vehicle unit 17

by virtue of marker 27 would be allowed to increase its speed to that permitted in zone 4 for its particular V-O classification of D; marker 28 indicates the beginning of zone 3, vehicle unit 18 having passed the right angle turn marker 28 would be allowed to increase its speed at marker 29 to that allowed in zone 5 for its particular V-O classification E; vehicle unit 19 would have to slow down to speeds of those allowed in zone 3, just having passed speed reduction markers 30 and 31.

Upon turning on the lights each of the vehicle units 8 to 19 inclusive, as will be explained later, would be declassified to the next lower classification; also upon the recognizing of bad driving conditions the same declassification would occur, and if these two factors should occur simultaneously then a double derating would be in effect. Then vehicle unit 14, for example, would have to reduce its speed for, although still traveling in zone 2 as shown by marker 25a, its classification would be reduced from C to E.

As each of the vehicles continues along the highway, its speed would have to be modified as directed by the respective zone markers. As vehicle 18, for instance, proceeds to marker 30,

31 and then 32, its speed would have to be progressively reduced from that allowed in zone 5 to that allowed in zone 4, zone 3, and then zone 2, if infraction of the law is to be avoided.

One possible form of signal given by the vehicle is shown in Fig. 7 where lamps 35, 36, 37, 38 and 39 are speed zone signals mounted on support 43. Means, as described later, are provided so that when the vehicle is traveling at speeds not exceeding those allowed in zone 1 for the particular overall equivalent classification of the vehicle under the conditions it is operated, then one signal 36 is illuminated indicating thereby an equivalent speed corresponding to that allowed in zone 1. When the speed of motion increases to that allowed above zone 1, but not beyond zone 2 then two signals 36 and 38 are given; in the particular arrangement shown, 36 would be white and 38 amber and on a horizontal line so as to correspond as closely as possible to the configuration, arrangement, color, etc. of the highway zone 2 marker shown in Fig. 2. Fig. 8 shows a detailed cross section of a vehicle signal where 43 is a supporting member and 35 is the signal light.

In a like manner, as speeds are increased one additional signal is given for each zone and the color, arrangement, etc. of the vehicle signals is similar to the highway zone marker. Signals 37 and 39 are white and signal 35 is amber. In the particular arrangement shown all five signals would be displayed whenever speeds ex-

ceeding those allowed in zone 4 were reached. That is, zone 5 is in reality a no-limit zone. By means, as will be described later, the signals in zone 5 may be made to flash on and off at a rate proportional to the vehicle's speed, thereby giving to others a measure of the actual rate of travel. Signals 40, 40a, and 40b located on the rear of the vehicle as indicated in Fig. 7 show respectively the recognition of bad driving conditions, the operation of the vehicle by a class 2 operator, and by a class 3 operator.

The license tag 41 by a particular code may be made to show the vehicle classification, or this classification may be shown by the auxiliary tag 42 attached thereto.

The speed zones, as shown by Fig. 1 to 5 inclusive and as indicated on map 6, mean different allowable speeds of travel for the different overall equivalent vehicle-unit classification, and the signals on the vehicle 35 to 39 inclusive represent rates of speed corresponding to those permitted by the vehicle for each zone while signals 40, 40a and 40b, markers 41 and 42, as well as the car tail lights 41a indicate respectively the recognition of bad driving conditions, the classification of the operator, the classification of the vehicle, and the recognition of light or darkness. Others may therefore check the overall classification of the unit or any individual factor making up its total equivalent classification. Assuming the classification to be correct, then if the number of signals 35 to 39 displayed exceeds the number of the zone in which the vehicle is traveling, violation would be self-evident. For instance, if three lights were showing in zone 2, violation would be obvious, and even to a greater extent if four lights were showing. Likewise, travel at slower speed than that designated by a particular zone would be evident if the number of signals were less than the zone number. Regulation against subnormal as well as abnormal speeds would be thus made practical.

One form of mechanism is shown on the drawings for indicating to the operator the allowable speeds in each zone for his particular overall vehicle classification as operated.

Referring to Fig. 13, the target 92 pivoted at 95 is placed behind the speedometer dial 96 in such a manner that the shaded and unshaded segments of target 92, characteristically representing allowable speeds in each zone for each classification, are made to appear through a slot 98 in dial 96 as the target is made to move about 95. Likewise classification letters A, B, C, etc. on target 92 are made to appear through aperture 99 in dial 96. In Fig. 13, the target is in the position of classification A and as it moves to the right (by means which will be described later) it assumes classification positions B to G inclusive, position G shown in dashed outline in Fig. 13. Likewise as it moves to the right, progressively lower and lower allowable speed ranges (in M. P. H.) are indicated through slot 98 for each zone. These, as arbitrarily used in the drawings, are shown in the first part of the following table, and their drawing reference characters in the second part. It is to be noted that this table differs from that shown on page 2 in both the miles per hour allowed in each zone and in the number of zones. Five instead of six, zones were selected for this example in order to simplify the drawings and explanation. The speed ranges shown were selected as an example of approximately uniform

increments in stopping distance for each higher zone.

The signals displayed for each zone are the same as for the example on page 2 except for zone 5. In this example, in zone 5, all five signals are not only displayed but also flashing at speeds corresponding to zone 5. As in the previous example speeds corresponding to the highest number zone might be legal in very sparsely populated areas but unlawful in others. In other words, legal or illegal operation is a relative matter and fundamentally is determined by comparing the position of the speedometer indicator 102 relatively to the segments of Fig. 14 with the highway zone marker which dictates the speed limits for the section of the highway in which the vehicle is traveling. As will be explained later, the position of pointer 102 relatively to the segments of Fig. 14 and their electrical counterpart contact 93 and the commutator segments of commutator 94, determine what signals are to be displayed, thereby giving a secondary way in which a determination may be made of legal or illegal speeds of travel.

Classification appearing through slot 99	Zone 1	Zone 2	Zone 3	Zone 4	Zone 5
A	0-22	22-34	34-43	43-41	Over 51.
B	0-18	18-28	28-36	36-43	Over 43.
C	0-14	14-24	24-31	31-37	Over 37.
D	0-11	11-21	21-27	27-32	Over 32.
E	0-9	9-17	17-23	23-28	Over 28.
F	0-8	8-14	14-19	19-24	Over 24.
G	0-7	7-13	13-17	17-21	Over 21.
A	92a	92b	92c	92d	92e.
B	92a	88b	88c	88d	92e.
C	92a	89b	89c	89d	92e.
D	92a	90b	90c	90d	92e.
E	92a	91b	91c	91d	92e.
F	92a	72b	72c	72d	92e.
G	92a	50b	50c	50d	92e.

Segments in the drawing having subscripts *a*, *c*, and *e* are shown as white, and *b* and *d* as amber, so as to provide an easily distinguishable zone marking and one having a similarity with the highway markers and vehicle zone signals; however, any arbitrary color code could be employed. Segments 98a and 98b on dial 96 represent the same characteristic markings as on target 92, namely 92e and 92e respectively.

The operator would not have to concern himself with his vehicle unit overall classification or his speed of travel in terms of miles per hour. It would simply be necessary for him to observe the markers on the highway and to see that the indicator 102 of his speedometer was at all times within or not in excess of the confines of the particular highway zone in which he was traveling as shown on target 92 through slot 98. The movement of this target and its calibrations together with the speedometer indicator 102 essentially form a new and convenient type of instrument for the effective guidance of the operator in the matter of safe operating speeds.

The position of target 92 is determined by the master classifying mechanism 300 (see Fig. 9) through sliding member 301, linked to target 92 by pin 302 into slot 97. A horizontal movement of member 301 causes a movement of target 92 about point 95, thereby showing the allowable speeds for each classification, as previously explained. Member 301 is fixed to the master classifying mechanism 300 at positions 305, 306, 307 or 308 by pin 304 inserted through holes in wall of tube 303. Insertion of pin 304 in one of the above equally spaced holes sets the

classification of the vehicle. When in hole 305 as shown, the vehicle classification is set as that of No. 1, and when in holes 306, 307, or 308 the classification is set at No. 2, No. 3 and No. 4 respectively. A means 308a is provided for sealing the pin in its proper classification position by the properly constituted authorities. When pin 304 is inserted and sealed into any one of its four possible positions, member 301 and tube 303 are thereby rigidly connected together, but 10 free to move axially in bearings 309 and 310.

The axial position of these members 301 and 303 is determined by cams 313, 314 and 315, end plate 312 of member 303 being held against the face of cam 313 by spring 311. All these cams, bearing 310, as well as spacer plates 316 and 317 are supported and restrained by suitable structural members 319 and 320. Cams 313 and 314 are free to slide in slot 321 along a line parallel to the axis of member 303 as well as to rotate about their own axes. Cam 315 is also free to rotate about its own axis but is restrained from sliding by its own bearings in structural member 319 and 320. In the position shown the distance from the axis of cam 315 to the face of cam 313 resting against end plate 312 is the greatest possible for any combination of cam positions.

The shape of cam 313 has been proportioned so that a 90° rotation will move members 303 and 301 a distance equal to the spacing between holes 305 and 306 in member 303, a distance that will cause target 92 to move from one classification position to the next. Cam 314 is of similar shape. When cam 314 is rotated 90°, separator plate 316 slides in slot 318 in structural members 319 and 320 while cam 313 slides in slot 321. Cam 315 has been shaped so that a 90° clockwise motion will cause a movement of member 301 equal to the distance between holes 305 and 306, a 90° counterclockwise motion will cause a movement of twice the distance between 305 and 306 and like the other two cams a 180° movement will result in no change in the position of member 301.

Cam 313 is caused to rotate 90° clockwise by turning light switch control knob 81 in instrument panel 45 from the "off" to the "on" position since this knob is connected to cam 313 by flexible shaft 83. Turning knob 81 also causes light switch 77 to be thrown to the "on" position completing a circuit from supply lead 47 to vehicle light circuit 77a. Bearing 83a supports shaft 83.

Cam 314 is caused to rotate 90° clockwise by turning driving condition control knob 73 from the "good" to the "poor" position since this knob is connected to cam 314 by flexible shaft 75. The same motion causes switch 76 to be thrown to the "on" position completing a circuit from lead 100 to 77b and energizing a suitable signal 40 that will inform others that the operator recognizes bad driving conditions. The turning of knob 73 to the "poor" position opens valve 78 in windshield wiper supply line 79, 65 making it possible to operate the windshield wiper if it is of the pneumatic type. Bearings 75a and 75b support shaft 75. If an electric

windshield wiper were used it would be connected to circuit 77b.

Other cams may be placed in series with cams 313 and 314 and similar classification movements obtained by either automatic or manual means.

Cam 315 is positioned by cable 69 directly connected to operator classification mechanism contained within lock housing 57. Directly connected to the cylinder of this mechanism is an auxiliary cam 49 which has as its function the blocking of access to the ignition lock 44 by the ignition key to others than those qualified, the seizing of the operator's classification key until the ignition key is removed and the operator's classification indication 57b returned to the "off" position, as well as the providing of a limit stop against block 60 for the No. 1 position.

In the particular arrangement shown, the lock is constructed so that the cylinder 53 may be caused to turn by three different operator classification keys, each permitting a certain selective motion. The mechanism (Figs. 16 to 22 inclusive) consists essentially of (1) an outside housing 57, (2) two like thin wall rings 56 and 56a placed side by side inside of housing 57 containing stops 63 and 65 respectively, (3) an inner cylinder 53 inside of rings 56 and 56a, having two slots, 62 opposite ring 56, and slot 66 opposite rings 56a, for limiting of its movement with respect to the stops 63 and 65 respectively, (4) two sets of two tumbler pins and associated spring contained in tumbler wells 53a opposite ring 56 and 53b opposite ring 56a, both wells extending from outside retaining cap 57a to center line of cylinder 53, (5) a key slot 53d in cylinder 53 extending axially and of a width slightly less than the diameter of the tumbler pins to prevent their falling beyond the limits of the tumbler wells, (6) three associated operator classification keys 52, 61 and 64 for class 1, 2, and 3 operators respectively.

Selective action is obtained by the three keys by (a) positioning tumblers so that rings 56 and 56a are made fast to cylinder 53 but free to turn within housing 57, (b) positioning tumblers so that ring 56 is made fast to cylinder 53 and free to turn within housing 57 but that ring 56a is made fast to housing 57 and therefore freedom of cylinder 53 restricted by stop 65 in slot 66, (c) positioning tumblers so that ring 56a is made fast to cylinder 53 and free to turn within housing 57 but that ring 56 is made fast to housing 57 and therefore freedom of cylinder 53 restricted by stop 63 in slot 62. Indicator 57b, free to turn in the panel, is arranged so that as the operator's classification key is turned, it moves to indicate the classification. The assembly is held together by restraining washers 54.

The following table sets forth an analysis of the operations of the mechanism, its associated electrical switch 50 and classifying cam 315 for each of the operator classification keys 52, 61 and 64. For reference, see Figs. 16 to 22 inclusive, where Fig. 19 represents section A—A, Fig. 20 section B—B, Fig. 21 section C—C, and Fig. 22 section D—D.

Key	Indicator 57b shows class—	Ring 56 fixed to—	Ring 56a fixed to—	Movement limited by—
52.....	I.....	Cylinder 53 by pin 59b.....	Cylinder 53 by pin 59d.....	Cam 49 and stop 60.
61.....	II.....	Cylinder 57 by pin 59a.....	Cylinder 53 by pin 59d.....	Stop 63 in slot 62.
64.....	III.....	Cylinder 53 by pin 59b.....	Housing 57 by pin 59c.....	Stop 65 in slot 66.
None.....	Off.....	Housing 57.....	Housing 57.....	Stops 63 and 65.

Key	Limit of motion	Electric circuit completed from	Position of cam 315	Position of target 92
52	180° clockwise 90° counterclockwise.	No contact	180° clockwise	No change.
61	90° clockwise	50 to 50a signal 40a	90° clockwise	One declassification.
64	90° counterclockwise	50 to 50b signal 40b	90° counterclockwise	Two declassifications.
None*	0°	None	No movement	No movement.

*Access to ignition lock 44 blocked by cam 49.

The arrangement shown was selected to give an example of one form of interlocking between an operator's classification means and the vehicle's master control element, the circuit of which could not be completed unless one or other of the proper operator classification means was employed. By this particular form it is not intended to convey the conception that the same operator classification keys would of necessity fit the lock mechanism on all vehicles. One set of operator's license keys might fit all private pleasure cars, another light trucks, another heavy trucks, another taxicabs, another busses, etc. That is, for instance, while a certain individual might be highly qualified to operate a private pleasure car and hold an official class 1 passenger car operator's license and associated key bearing his license number, he might not possess sufficient qualifications as a class 1 truck operator. On the other hand, it might practically follow that a class 1 truck driver would be sufficiently qualified as a class 1 pleasure car operator and his key could be designed to fit both locks making, in that instance, the carrying of duplicate operator's keys unnecessary.

The position of target 92, calibrated to provide a ready reference zone speed guide for the operator, is therefore controlled by the position of pin 304 as sealed by the authorities in classifying the vehicle, by the turning "on" and "off" of the vehicle lights, knob 81, by the turning of knob 73 when recognizing wet or slippery pavement, abnormal traffic congestion, etc., by the operation with officially granted license keys of the operator's classification mechanism, or by any other similar automatic or manual means.

As connecting rod 301 is made to move by the master classifying mechanism 300, connecting pin 301a in slot 301b causes arm 301c pivoted at center 301d to move contact 93 over face of commutator 94 to the corresponding classification lanes A, B, C, etc. Each of these lanes is simply a position and not an insulated section of the commutator; they, however, determine the speed at which contact 93 completes an electrical circuit to the zone signal segments 105, 107, 109, 111, 112 or 113 of commutator 94. Shaft 104, through suitable instrumentalities, is made to turn at a speed proportional to the speed of the vehicle; this action, in turn, through speed responsive means 103 and shaft 101, causes commutator 94 to be positioned in proportion to the vehicle's speed. Commutator 94 and contact 93 therefore become the meeting ground for the initiation of signals in proportion to the vehicle's speed and in accordance with its selected overall classification.

Fig. 23 shows a developed view of this commutator, its insulated segment, adjustable sliding contact 93, as well as the complete wiring diagram for the giving of all signals associated with my invention.

Potential is supplied from a battery or source 147 through lead 47 to (1) light switch 77, lead

77a to vehicle lights, (2) ignition switch 46, lead 100 to driving condition switch 76, lead 77b to external signal 40 mounted on the rear of the vehicle, (3) ignition switch 46, lead 100 to operator classification switch 50, leads 50a or 50b to driver classification signals 40a and 40b, (4) ignition switch 46, lead 100 to commutator 94, associated relays, signals and recorders. One group of these signals 35, 36, 37, 38 and 39 referred to previously are speed zone signals mounted on the top of the vehicle. Another group 185, 150, 187, 170 and 180 are also speed zone signals but these are mounted inside the vehicle on the panel board behind translucent caps 185', 150', 187', 170' and 180'. A third group are speed zone recorders 172, 172a, 186, 188 and 188a. In addition to these there is a zone change warning light 177 and a zone change warning bell 178, which may both be mounted on the instrument panel.

The function of the relays and associated equipment is twofold, first, to permit the commutator 94 to handle comparatively small currents instead of the full signal currents and second, to delay the giving of certain signals a predetermined short interval as will be subsequently described.

Potential from lead 100 is supplied to the sliding contact 93 which in turn supplies potential to the selected commutator segment. From these segments are leads to the coil circuits of auxiliary relays 131 to 136 inclusive, which either cause certain signals to be given at once or at some later predetermined interval. These auxiliary relays are energized in the following manner, one at a time depending upon the position of sliding contact 93 on commutator 94 (the special case of contact 93 completing the circuit to two commutator segments simultaneously will be treated later): When contact is made to segment 105 (legal stop segment) a circuit is completed to lead 106 to coil 197 of relay 136; when contact is made to segment 107 (zone 1 segment) a circuit is completed to lead 108 to coil 148 of relay 131; when contact is made to segment 109 (zone 2 segment) a circuit is completed to lead 110 to coil 151 of relay 132; when contact is made to segment 111 (zone 3 segment) a circuit is completed to lead 114 to the coil of relay 133; when contact is made to segment 112 (zone 4 segment) a circuit is completed to lead 115 to the coil of relay 134; and when contact is made to segment 113 (zone 5 segment) a circuit is completed to lead 116 to the coil of relay 135.

Assuming a commutator position such that auxiliary relay 131 will be energized, then its "break" contact 163 will be open. All the other relays will be de-energized and potential will be supplied from lead 100 to lead 164a through a pair of "break" contacts of relay 145 to lead 164 to lead 165 to No. 1 zone external signal 36 and internal signal 150. Next assuming a vehicle speed increase or a declassification movement of contact 93 such that relay 131 is de-energized and relay 132 energized, then signals 36 and 150

will still be displayed through de-energized contacts of relay 145, for only relay 132 will be energized. At the same time "break" contacts 152b of relay 132 will be opened and potential supplied from lead 100 to lead 166b through "make" contacts 152a to heating element 153 of time delay thermal relay 137, through "break" contacts 154 of de-energized relay 142 to common ground return lead 155 to battery, also another circuit from contacts 152a through lead 173, "break" contacts 174 of relay 142 through rectifier 175 to lead 176 to warning bell 178 and warning light 177, both located inside the car on the operating panel, through lead 179 to ground. After a short time delay, bimetal strip 156 of relay 137 makes contact with 157 carrying positive potential from contacts 152a of relay 132 through lead 161 to coil 158 of relay 142, thereby energizing this relay which in turn opens contacts 154 in heater circuit of relay 137.

Relay 142 seals itself closed through its "make" contacts 160, the complete circuit being from lead 100 through contacts 163 of relay 131, lead 163a, lead 162, contacts 160, lead 161, to coil 158. As long as relay 131 remains de-energized, the sealing circuit will be complete. The energizing of relay 131, such as would occur with vehicle speed being reduced to that corresponding to zone 1, would immediately de-energize relay 142, since the thermal element contact 156 would be in the "cold" or "off" position and therefore unable to supply potential to coil 158. At the time relay 142 was energized, the warning signal circuit through contact 174 was broken and a display signal circuit completed through contacts 167.

The completion of contacts 167 provided the following source of supply to the signals; from lead 100 to lead 164a, contacts 164b of relay 145, lead 164 to contacts 167 to lead 169 to external display signal 38 and internal display signal 170. As the vehicle speed is increased to that of zone 3, relay 133 is energized and relay 132 de-energized.

The energizing of relay 133 sets up an exactly similar time delay circuit as that previously described. In this instance, the circuit is set up through relays 138 and 143 and warning signals are given as previously described until relay 138 closes, in turn closing relay 143 which seals itself in through its bottom contacts and contacts 152b of relay 132 as well as contacts 163 of relay 131. Therefore relay 143 will remain closed until either relay 132 or 131 is energized removing its sealing supply. The closing of relay 143 completes through lead 180a a supply circuit to signals 39 and 180. The circuit from contacts 182 of relay 133 through rectifier 183, lead 184 to lead 161 and coil 158 of relay 142 is provided for the purpose of energizing relay 142 immediately upon the energizing of relay 133 regardless of whether relay 137 had had time to complete its circuit. This connection has the two-fold purpose of giving the lower speed signal when the speed is reduced from one segment to the next, and also of preventing the signal from lagging the speed by more than one step at a time on rapid acceleration. In a like manner, relay 134 upon closing provides a source of supply through rectifier 183a, lead 184a, to coil of relay 143 and also through rectifier 184b, rectifier 183, lead 184, lead 161, to coil 158 of relay 142, immediately closing relays 142 and 143, upon the energizing of relay 134. When relay 134 closed it set up a timing circuit through relay 139 and relay 144,

giving the warning signals. Then when relay 144 closed it energized signals 35 and 185 through contacts similar to those described for the previous relays.

- 5 In a like manner, similar circuits are set up by the closing of relay 135 and the energizing of time delay relay 140. Signals 37 and 187 are displayed upon the closing of relay 145, making a total of five signals displayed to others as well as the operator, denoting a vehicle speed corresponding to that allowed in zone 5. Relay 145, however, is provided with five sets of contacts instead of four as are relays 142, 143 and 144. This additional set of contacts 164b is opened 10 upon the closing of relay 145, thereby removing a short circuit between leads 164a and 164, leaving resistor 190 a circuit breaking device 195, Fig. 24, in parallel between the two leads. Internal dash board display lamps 185, 150, 187, 170 and 130 are connected in parallel with lamps 35, 36, 37, 38 and 39 just described. Indicators 185', 150', 187', 170' and 189' are transparent color caps on the dash board through which the lamp signals are displayed. Device 195 is connected to shaft 104 which revolves at a rate proportional to the vehicle's speed. Its periphery is made up of two segments, 197 being a contacting surface and 198 an insulating surface. As 195 revolves, a circuit from lead 191 through contact 194, commutator 195, contact 193, and lead 192 is made for a half revolution and opened for the next half revolution. During the half revolution in which the circuit is made, a short circuit in reality still exists between leads 164a and 164 25 and full potential is available to all of the signals displayed. During the half revolution that the circuit between 194 and 193 is broken, then the supply to the signals from lead 100 to lead 164 is through resistor 190 which introduces a high 30 potential drop. As 195 revolves, the display signals are caused to flash on and off at a rate proportional to the speed at which 195 revolves and therefore in proportion to the speed of the vehicle. By suitable gearing the flashing may be 35 made to occur at a relatively slow rate so that by counting the flashes during a definite period of time the speed of the vehicle could be determined.

Solenoids 172, 172a, 186 and 188 are energized 40 whenever relays 142, 143, 144 and 145 respectively are energized. These solenoids cause registers to record the miles traveled in each zone and the number of times the speeds corresponding to that particular zone were reached. Solenoid 188a causes a recording of the number of stops. Lead 171 is connected to energize solenoid 172 and lead 183b supplies solenoid 172a.

Returning to the special case of contact being 45 made to two zone segments of commutator 94 simultaneously; should this occur and for instance cause both relays 132 and 133 to be closed then "break contact" 152b would open the sealing circuit to relay 143, immediately opening it if it were closed. If the condition continued for some time, then relay 143 would open and close slowly.

When the vehicle is brought to a stop, commutator segment 105, extending from about zero to one mile per hour, of commutator 94 is energized from brush contact 93 through lead 106 to coil 197 of relay 136 which causes "make" contacts 198 to be closed. Contact 198 energizes lead 200 to resistor 201 of time delay relay 141 and coil 202 of relay 146. Energizing of coil 202 causes "make" contacts 203 and 204 to be

closed, contacts 204 and associated leads sealing relay coil 197 in closed position operating register 188a, lamp 177, and bell 178 and causing all speed zone signals to be displayed through lead 205 to relay 145 and through rectifier 206 to relays 144, 143 and 142. The connections to the thermal element 207 of relay 141 are such as to open supply to coil 202 of relay 146 after a predetermined short interval of time, regardless of whether coil 197 is still energized through lead 106 or not. When relay thermal element opens, resistors 201a and 201 are placed in series reducing the heating effect, should the vehicle remain in the stopped position for a considerable time.

Fig. 27 shows a panel view of zone registers. Shaft 208 in Fig. 26 is driven through suitable gearing from drive shaft of vehicle. Gear 209 is keyed to shaft 208. At top of gear 209 is a gear 210 on movable shaft 211. One end of shaft 211 connects to a cyclometer 212 supported on trunnions 213. The other end of shaft 211 is supported by bearing and structural member 214. This member 214 is held in an upward position by spring 215 and thereby causes gear 210 to be disengaged from main driving gear 209. When magnet 188 is energized, however, member 214 is pulled down which brings shaft 211 down and gear 210 into mesh with large gear 209 and causes cyclometer 212 to register in terms of miles, distance traveled, while coil 188 is energized. As previously explained, this coil 188 is energized whenever the vehicle is traveling at a speed corresponding to that allowed in zone 5. Therefore, the cyclometer 212 registers miles traveled by vehicle when speed corresponds to that allowed in zone 5, all conditions of vehicle classification, operator's classification, driving conditions, visibility, etc. having been taken into account automatically.

At the same time that shaft 211 was pulled down by the energizing of coil 188, lever 216 was also pulled down through spring 217, the pulling down of lever 216 having caused the counter 218 to make one registration. Therefore, while the cyclometer 212 is registering the miles traveled, the counter 218 registers one for each time a speed is reached corresponding to that allowed in zone 5.

Fig. 27 shows an example of the appearance of the cyclometers and counters as may be viewed through the panel board 226. The cyclometers 219, 220, 222, 224 and 212 record respectively total miles traveled, miles traveled at speeds corresponding to No. 2 zone and higher, miles traveled at speeds of No. 3 zone and higher, miles traveled at No. 4 zone speeds and higher, and miles traveled at No. 5 zone speeds. Counters 227, 221, 223, 225 and 218 register respectively total number of times vehicle was brought to legal stop and total number of times the signal relays for No. 2, 3, 4, and 5 zone signals were energized.

It is understood in this proposed method of speed control as set forth herein that the method need not be adopted in its entirety by any or all authorities, nor even in fact that legal authorities adopt any part of the invention. It obviously has direct advantages without legal enactment, particularly as a safety guide to operators and for fleet owners. Some legal authorities may elect to not classify operators, others may elect to not classify vehicles, etc. Some may adopt only the speed zone marker system.

As shown in this specification, each derating

derates the vehicle by a unit classification. It is, of course obvious that other instrumentalities may be employed or the examples given modified to derate the vehicle in fractional or greater than a unit derating for certain conditions.

The disclosed and other forms of the pieces of apparatus I employ as instrumentalities by means of which I carry out the provisions of my improved method or system of traffic control, I reserve for divisional application covering specific features thereof.

Having thus described my invention what I claim is:

1. In a system for regulating over a highway the speed of different classes of vehicles under different conditions of driving and under different classes of drivers, the combination of indicating means arranged on the highway in different zones thereof and indicating for each zone the permissible speed therein for a preselected class of traffic under preselected drivers and driving conditions, indicating means on the vehicles capable of giving variable indications corresponding to the different highway indicating means and thereby indicating whether or not a vehicle complies with said highway indicating means, and means controlled by the substantial cessation of the speed of the vehicle for causing said second mentioned indicating means to display a legal stop signal for a predetermined interval of time.
2. In a system for regulating over a highway the speed of different classes of vehicles under different conditions of driving and under different classes of drivers, the combination of indicating means arranged on the highway in different zones thereof and indicating for each zone the permissible speed therein for a preselected class of traffic under preselected drivers and driving conditions, indicating means on the vehicles capable of giving variable indications corresponding to the different highway indicating means and thereby indicating whether or not a vehicle travels at a permissible speed, means controlled by the speed of the vehicle for causing said second mentioned indicating means to display said variable indications after a predetermined lapse of time, and means for modifying said speed-controlled means to adjust it for different classes of vehicles and different conditions of driving, said means comprising means accessible only to properly constituted authorities for limiting the control of the speed-controlled means upon the indicating means in accordance with the class of vehicle and driver thereof, and further means operable by the driver, as an incident to changed driving conditions requiring a reduction in speed to further limit the control of said control means.
3. In a system for regulating over a highway the speed of vehicles under different conditions of driving, the combination of indicating means arranged on the highway in different zones thereof and indicating for each zone the permissible speed therein for variable preselected driving conditions, indicating means on the vehicles capable of giving variable indications corresponding to the different highway indicating means and thereby indicating whether or not a vehicle travels at a permissible speed, means controlled by the speed of the vehicle for causing said second mentioned indicating means to display said variable indications, and means for modifying said speed-controlled means and operable as an incident to recognition by the driver of changed

driving conditions which require modification of speed.

4. In a system for regulating over a highway the speed of different classes of drivers, the combination of indicating means arranged on the highway in different zones thereof and indicating for each zone the permissible speed therein for a preselected class of drivers, indicating means on the vehicles capable of giving variable indications corresponding to the different highway indicating means and thereby indicating whether or not a driver travels at a permissible speed, means controlled by the speed of the driver for causing said second mentioned indicating means to show said variable indications, and means for modifying said speed-controlled means to adjust it for different classes of drivers.

5. In a system for regulating over a highway the speed of different classes of vehicles, the combination of indicating means arranged on the highway in different zones thereof and indicating for each zone the permissible speed therein for a preselected class of vehicles, indicating means on the vehicles capable of giving variable indications corresponding to the different highway indicating means and thereby indicating whether or not a vehicle travels at a permissible speed, means controlled by the speed of the vehicle for causing said second mentioned indicating means to show said variable indications, and means for modifying said speed controlled means to adjust it for different classes of vehicles.

6. In a system for regulating over a highway the speed of different classes of vehicles, the combination of indicating means arranged on the highway in different zones thereof and indicating for each zone the permissible speed therein for a preselected class of vehicles, indicating means on the vehicles capable of giving variable indications corresponding to the differ-

ent highway indicating means and thereby indicating whether or not a vehicle travels at a permissible speed, means controlled by the speed of the vehicle for causing said second mentioned indicating means to show said variable indications, and means for modifying said speed controlled means to adjust it for different classes of vehicles, said means comprising means accessible only to properly constituted authorities for limiting the control of the speed-controlled means upon the indicating means in accordance with the class of vehicle.

7. In a system for regulating over a highway the speed of different classes of vehicles under different conditions of driving and under different classes of drivers, the combination of indicating means arranged on the highway in different zones thereof and indicating for each zone the permissible speed therein for a preselected class of traffic under preselected drivers and driving conditions, indicating means on the vehicles capable of giving variable indications corresponding to the different highway indicating means and thereby indicating whether or not a vehicle travels at a permissible speed, means controlled by the speed of the vehicle for causing said second mentioned indicating means to display said variable indications, and means for modifying said speed-controlled means to adjust it for different classes of vehicles and different conditions of driving, said means comprising means accessible only to properly constituted authorities for limiting the control of the speed-controlled means upon the indicating means in accordance with the class of vehicle and the driver thereof, and further means operable by the driver, as an incident to changed driving conditions requiring a reduction of speed, to further limit the control of said control means.
